SLEEVE BOARD BRACKET SUPPORT FOR IRONING BOARDS

Harlan A. Salmon, Washington, D. C.

Application March 12, 1935, Serial No. 10,710

10 Claims. (Cl. 68—10)

This invention relates to certain new and useful improvements in sleeve board bracket supports for ironing boards.

The primary object of the invention is to provide a sleeve board attachment for ironing boards wherein a novel form of bracket support is interposed between the ironing and sleeve boards with the latter restrained from movements relative to the ironing board when extended for use and retracted into an inoperative position.

A further object of the invention is to provide a bracket support for attaching a sleeve board to an ironing board wherein the bracket support includes a pair of bracket arms respectively secured to the undersides of the ironing and sleeve boards with the bracket arms relatively movable and cooperatively constructed to be restrained from relative movement when the sleeve board is extended for use and retracted to a position underlying the ironing board.

With the above and other objects in view that will become apparent as the nature of the invention is better understood, the same consists of the novel construction, combination, and arrangement of parts to be hereinafter more fully described and then claimed.

In the accompanying drawing:—

Figure 1 is a top plan view of an ironing board with the sleeve board attachment therefor and illustrating the bracket support between the ironing and sleeve boards with the sleeve board positioned laterally of the ironing board.

Figure 2 is a side elevational view with the supporting legs of the ironing board fragmentarily illustrated and with the sleeve board set up in operative position.

Figure 3 is a cross-sectional view taken on line 3—3 of Figure 2 showing the two bracket arms of the support with the pivotal pin and slot connection therebetween with the bracket arm carried by the sleeve board supported on the bracket arm carried by the ironing board in extended position.

Figure 4 is a cross-sectional view, similar to Figure 3, showing the sleeve board folded to a position beneath the ironing board with the bracket arm carried by the sleeve board supported on the bracket arm carried by the ironing board with the sleeve board and bracket arm carried thereby illustrated by dotted lines in its path of movement from operative to inoperative positions, and

Figure 5 is a detail sectional view taken on line 5—5 of Figure 1, showing the connection between

the sleeve board and the double bracket arm support.

Referring more in detail to the accompanying drawing, the reference character 10 designates an ironing board of the usual design and construction adapted to be supported by legs or braces 11 fragmentarily illustrated in Figure 2 and said ironing board 10 has a sleeve board 12 adjustably associated therewith for movement to a position laterally of and above the plane of the ironing board when in use and for retracting or folding movement when out of use to a position underlying the ironing board.

The connection between the sleeve board and ironing board comprises a bracket support in the form of spaced pairs of bracket arms, the arms 13 and 14 of each pair being respectively secured to the ironing board 10 and sleeve board 12 and embodying pivotal and interlocking connections.

As shown more clearly in Figures 1, 2, and 5 the bracket arms 14 are secured at their outer ends in any convenient manner to the angle flanges 15 at the ends of the connecting bar 16 for the arms. A substantially U-shaped strap member has the base portion 17 thereof secured to the underside of the sleeve board 12 with the depending divergent legs 18 engaged with the connecting bar 16. One of the legs 18 has a rolled hook 18^a at its lower terminal end for pivotal placement in an opening adjacent one end of the bar 17 and is engaged by the lug 19 struck-out from said opening. The lower terminal end 18^b of the other leg 18 passes through an opening in the bar 16 and is frictionally engaged by the adjacent lug 19. The sleeve board 12 and the strap member may be disengaged from the connecting bar 16 by first removing the end 18^b of the leg 18 against friction thereon and pivotally disengaging the leg hook 18^a from the bar 16.

The bracket arms 13 are shown more clearly in Figures 3 and 4, the upper edge of the bracket arm 13 carrying angle flanges 20 to facilitate attachment of the bracket arm 13 to the underside of the ironing board 10. The bracket arms 13 and 14 are of blade-like formation and the connection between the two bracket arms includes the provision of an elongated slot 21 in the bracket arm 13 and a headed pin 22 projecting laterally of the free end of the bracket arm 14 with the pin 22 riding and being retained in the slot 21. This form of connection between the bracket arms 13 and 14 permits pivotal and sliding movement of the bracket arm 14 relative to the bracket arm 13.

To hold the bracket arm 14 in its extended position as illustrated in Figure 3 with the sleeve board 12 in service, a laterally directed lug 23 is struck-out from the upper edge of the bracket 5 arm 14 and is adapted to be received in the upper edge opening notch 24 formed in the adjacent end of the bracket arm 13. The pin and slot connection cooperates with the lug and slot connection between the arms for holding the two 10 arms in alinement and the sleeve board rigidly supported in position for use.

The bracket arm 14 is adapted to be moved in the path of movement indicated by dotted lines in Figure 4 to assume the full line position when 15 out of use and be supported in alinement with the bracket arm 13 and with the sleeve board 12 disposed beneath the ironing board 10 and to accomplish this positioning of the bracket arm 14 and sleeve board, the lower edge of the bracket 20 arm 13 as shown in Figures 3 and 4 is cut away as at 25 with a hooked member 26 projecting into the cut-away portion to form a seat 27 that is adapted to receive through the cut-away portion the lug 23 on the bracket arm 14 as shown in 25 Figure 4.

As stated, the cooperating arms 13 and 14 are arranged in spaced pairs and the arms 13 are anchored to the underside of the ironing board while the free ends of the arms 14 are connected by the bar 16 to which the sleeve board 12 is attached. With the sleeve board 12 set up for use as shown in Figures 1 to 3 and it being desired to shift the sleeve board to its inoperative position out of use beneath the ironing board, 30 the bracket arms 14 are raised at their outer ends by means of the sleeve board with the pins 22 pivoting in the slots 21 of the bracket arms 13 for removal of the lugs 23 from the recesses 24 in the bracket arms 13. The arms 14 are then 35 slid outwardly of the bracket arms 13 to position the lugs 23 outwardly of the adjacent ends of the bracket arms 13 and at which time the bracket arms 14 and sleeve board are swung downwardly as indicated by dotted lines in Figure 4 and upwardly to cause the lugs 23 to enter the cut-away portions 25 in the bracket arms 13 to position the lugs 23 in the seats 27. It will be observed that the bracket arms 13 are 40 each provided with a notch or seat at their upper and lower edges for selective reception of the single lug 23 carried by the bracket arm 14 to form an interlocking connection between the two bracket arms and with the bracket arms 14 rigidly supported in selectively reversed positions 45 alined and parallel with the bracket arm 13.

From the above detailed description of the invention, it is believed that the construction and operation thereof will at once be apparent and while there is herein shown and described 50 the preferred embodiment, it is nevertheless to be understood that minor changes may be made therein without departing from the spirit and scope of the invention as claimed.

I claim:

1. In a device of the character described, a sleeve board adapted for positioning beneath an ironing board when out of use and exposed relative to the board when in use, an adjustable bracket connection between the underside of the ironing board and sleeve board including cooperating bracket arms respectively carried by the two boards and interfitting connections between the bracket arms for holding the same in the same plane when the sleeve board is in either 60 operative or inoperative position.

2. In a device of the character described, a sleeve board adapted for positioning beneath an ironing board when out of use and exposed relative to the board when in use, an adjustable bracket connection between the underside of the ironing board and sleeve board including cooperating bracket arms respectively carried by the two boards, one of said arms having notches respectively in its upper and lower edges, a lug carried by the other arm for selective reception in the notches for supporting the bracket arms in alignment and a translatable pivotal connection between the bracket arms comprising a pin carried by one arm and the other arm having a slot through which the pin slidably extends. 10

3. In a device of the character described, a sleeve board adapted for positioning beneath an ironing board when out of use and exposed relative to the board when in use, an adjustable bracket connection between the underside of the ironing board and sleeve board including cooperating bracket arms respectively carried by the two boards, one of said arms having notches respectively in its upper and lower edges, a lug carried by the other arm for selective reception in the notches for supporting the bracket arms in alignment and a pin and slot connection between the bracket arms. 15

4. In a device of the character described, a sleeve board adapted for positioning beneath an ironing board when out of use and exposed relative to the board when in use, an adjustable bracket connection between the underside of the ironing board and sleeve board including cooperating bracket arms respectively carried by the two boards, one of said arms having notches respectively in its upper and lower edges, a lug carried by the other arm for selective reception in the notches for supporting the bracket arms in alignment and a pin and slot pivotal connection between the bracket arms intermediate the ends thereof. 30

5. In a device of the class described, an ironing board, a sleeve board attachment therefor, a bracket support between the ironing and sleeve boards including pairs of arms with an arm of each pair respectively secured to the ironing and sleeve boards, a pin and slot pivotal connection between each pair of arms, the arms carried by the ironing board having a pair of notched seats 45 in their respective upper and lower edges and a lug carried by each arm on the sleeve board for selective reception in the notched seats for the support of the sleeve board in extended operative position laterally of the ironing board or in retracted position beneath the ironing board. 50

6. In a device of the class described, an ironing board, a sleeve board attachment therefor, a bracket support between the ironing and sleeve boards including pairs of arms with an arm of each pair respectively secured to the ironing and sleeve boards, a pin and slot pivotal connection between each pair of arms, the arms carried by the ironing board having a pair of notched seats in their respective upper and lower edges, a lug carried by each arm on the sleeve board for selective reception in the notched seats for the support of the sleeve board in extended operative position laterally of the ironing board or in retracted position beneath the ironing board, said bracket arms being of blade-like form and laterally contacting each other. 65

7. In a device of the class described, an ironing board, a sleeve board attachment therefor, a bracket support between the ironing and sleeve 70

boards including pairs of arms with an arm of each pair respectively secured to the ironing and sleeve boards, a pin and slot pivotal connection between each pair of arms, the arms carried by the ironing board having a pair of notched seats in their respective upper and lower edges and a lug carried by each arm on the sleeve board for selective reception in the notched seats for the support of the sleeve board in extended operative position laterally of the ironing board or in retracted position beneath the ironing board, the connection between the sleeve board and bracket arms attached thereto including a bar connecting the adjacent ends of the bracket arms and an inverted substantially U-shaped strap interposed between the bar and sleeve board to elevate the latter relative to the bracket arms and ironing board.

8. In a device of the character described, a sleeve board adapted for positioning beneath an ironing board when out of use and exposed relative to the board when in use, an adjustable bracket connection between the underside of the ironing board and sleeve board including cooperating bracket arms respectively carried by the two boards, said bracket arms overlapping and the bracket arm carried by the sleeve board adapted to be immovably supported on the other bracket arm in reversely extending directions in the same horizontal plane.

9. In a device of the character described, a

sleeve board adapted for positioning beneath an ironing board when out of use and exposed relative to the board when in use, an adjustable bracket connection between the underside of the ironing board and sleeve board including cooperating bracket arms respectively carried by the two boards, said bracket arms overlapping and the bracket arm carried by the sleeve board adapted to be immovably supported on the other bracket arm in reversely extending directions in the same horizontal plane, the connection between the bracket arms including a translatable pivotal connection, one of the bracket arms having a pair of edge opening notches respectively in the upper and lower edges and at opposite sides of the pivotal connection and a lug on the other bracket arm for selective supporting reception in the notches.

10. In a device of the class described, an ironing board, a sleeve board attachment therefor, a bracket support between the ironing and sleeve boards including pairs of arms with an arm of each pair respectively secured to the ironing and sleeve boards, an inverted substantially U-shaped strap carried by the sleeve board, an apertured bar connecting the arms associated with the sleeve board and a pivotal hook and wedge connection between the legs of the strap and the apertured bar.
